UNITED STATES PATENT OFFICE.

FRANK S. JONES, OF PHILADELPHIA, PENNSYLVANIA.

GEARING FOR METAL WORKING MACHINES.

Application filed February 13, 1923, Serial No. 618,786. Renewed March 1, 1927.

My invention relates to metal cutting machines of the boring mill type adapted to perform a number of operations which ordinarily require separate machines.

5 The objects are to provide new and improved controlling means for such machines whereby quick and accurate manipulation is possible when working metal of any size or shape; to provide power controlling means 10 and hand controlling means having fewer parts than heretofore deemed possible, thereby reducing the up-keep to a minimum, and increasing the accuracy to a maximum.

These objects, and other advantageous 15 ends, which will be described hereinafter, I attain in the following manner, reference being had to the accompanying drawings in which

Figure 1 is a front elevation of a machine embodying my invention,

Figure 2 is a side view of Figure 1,

Figure 3 is a section taken on the line 3—3 of Figure 2,

Figure 4 is a section taken on the line 25 4—4 of Figure 3,

Figure 5 is a section taken on the line 5—5 of Figure 4,

Figure 6 is a section taken on the line 6—6 of Figure 5,

0 Figure 7 is a section taken on the line 7—7 of Figure 4,

Figure 8 is a section taken on the line 8—8 of Figure 7, drawn on a smaller scale,

Figure 9 is a section taken on the line 25 9—9 of Figure 7, also drawn on a smaller scale,

Figure 10 is a developed section of change speed gearing taken substantially on the line 10—10 of Figure 4, also partly showing the feed mechanism,

Figure 11 is a developed section of a shifting gear and hand controlling means,

Figure 12 is a face view of the back plate 45 of the saddle showing the arrangement of certain gears.

Briefly, the invention includes transmission of power through the speed change gearing to actuate the feed change gearing; means for connecting the feed change gearing with mechanism for imparting endwise movement to the spindle, vertical movement to the saddle or horizontal movement to the column; means for reversing the movements; independent means for reversing the movement of the feed change gearing; means for

effecting a rapid traverse of spindle, saddle or column, and a more rigid mounting for the spindle.

Referring to the drawings, the numeral 1 indicates a base; 2 a column; 3 a reversing 60 motor; 4 a saddle slidably mounted on the column; 5 a vertical splined drive shaft passing through the back of the saddle, which derives its power from the motor; 6 a rotatably mounted bevel gear slidably 65 keyed to the drive shaft 5 and meshing with a bevel gear 7 fixed to a spur gear 8 rotatably mounted on a fixed shaft 9.

Speed change gearing.

70 Spur gear 8 meshes with a gear 10 fixed to a pinion 11 keyed to a shaft 12 mounted in bearings cast integrally with the saddle. The pinion 11 meshes with a gear 13 on a shaft 14 mounted in bearings cast integrally 75 with the saddle. Shafts 12 and 14, herein-after called series shafts, have series gears mounted thereon. Shaft 12 has rotatably mounted series gears 15 and 16, which are designed with clutch engaging parts 15^a and 16^a respectively, to engage clutch members 17 and 18 fixed to shaft 12, and shaft 14 has a fixed series gear 19 adapted to mesh with series gear 16. The series gears 15 and 16 are cast together and have between them an 80 annular groove into which fits the end of an arm 15^b actuated by a lever 16^b outside of the saddle.

A shaft 20, journaled in bearings cast integrally with the saddle, has fixed thereto 90 intermediate gears 21, 22, 23 and 24 adapted to mesh with their respective speed change gears 25, 26, 27 and 28 slidably keyed to a shaft 29 journaled in bearings cast integrally with the saddle. The gears 25 and 26 are 95 cast together and have between them an annular groove 30, in which fits a yoked member 31 secured to a square shifting rod 32 sliding in bearings fixed to the saddle. Gears 27 and 28 are cast together and have 100 between them an annular groove 33, into which fits a yoked member 34 fixed to a square shifting rod 35 sliding in bearings fixed to the saddle. Shifting rods 32 and 35 have notches 36 and 37 on their adjacent 105 faces adapted to receive the end of a shifting lever 38 universally mounted on a bracket fixed to the saddle. Shaft 29 extends out of the saddle and has keyed thereto a driving pinion 39 which meshes with a bull gear 40 110

fixed to a sleeve 41, journaled in main bearings 42 and 43, and having a spindle or tool bar 44, slidably keyed therein, to which cutting tools may be secured in the usual manner.

The operation of the speed gearing is as follows: Three series of speeds with four speeds to each series are transmitted to the spindle 44 through the series shafts, series 10 gears and speed change gears. The first series of speeds are transmitted to shaft 20 through the series shaft 14, fixed series gear 19, rotatably mounted series gears 16 and 15 and gear 23. The four speeds are transmitted to the spindle 44 through either of the shifting gears 25, 26, 27 or 28 by shifting them, by means of the universally mounted lever 38, into mesh with their respective gear 21, 22, 23 or 24.

20 The second series of speeds is transmitted to shaft 20 through series shaft 12, clutch member 17, series gear 15 and gear 23.

25 The third series of speed is transmitted to shaft 20 through series shaft 12, clutch member 18, series gear 15 and gear 24.

30 The eight speeds of the second and third series are transmitted to spindle 44 by shifting either of the gears 25, 26, 27 and 28 in mesh with its respective gear 21, 22, 23 or 24.

Change feed gearing and reversing mechanism therefor.

Shaft 29 has a gear 45 frictionally coupled 35 thereto and hereinafter called a friction gear. Gear 45 meshes with a gear 46 integral with a gear 47 rotatably mounted on a fixed shaft 48. The frictional coupling permits gear 45, in case of sudden or excessive 40 strains, to rotate relatively to its shaft thereby avoiding danger of stripping the gears. The gear 47 meshes with gear 49 cast integrally with bevel gear 50 meshing with bevel gear 51 which in turn meshes with 45 another bevel gear 52. Bevel gears 50 and 52 are rotatably mounted on a shaft 53, and bevel gear 51 is rotatably mounted in a bearing fixed to the saddle. A clutch 54 slidably keyed to shaft 53 is moved, by an arm 50 55 actuated by a lever 56, to engage either of the clutch faces 57 or 58 on bevel gears 50 and 52 to impart forward or reverse movement. The parts beginning with the reference character 50 and ending with 58 55 constitute the reversing mechanism for the feed change gears. A shaft 53, which is journaled in bearings cast integrally with the saddle, has fixed thereto a gear 59, which meshes with a gear 60 of a group of gears 60, 61, 62, 63, 64, 65, 66, 67 and 68, to impart 60 a movement to a selective series of gears.

Gears 60, 62, 64 and 66 are respectively fixed to rotatably mounted pinions, 61, 63, 65 and 67. Pinion 61 meshes with gear 62, 66 pinion 63 with gear 64, pinion 65 with gear

66 and pinion 67 with gear 68. Pinions 61 and 65 are rotatably mounted on a shaft 69, gear 68 is fixed to shaft 69 to prevent endwise movement, and pinions 63 and 67 are rotatably mounted on a shaft 69^a fixed to 70 the saddle. A gear 70, slidably keyed on a shaft 71, has an annular groove 72 adapted to receive the end of an arm 73 actuated by a lever 74, and may be moved into engagement with either of the feed series gears 60, 75 64 or 68. Shaft 71 is mounted in bearings cast integrally with the saddle and has an angular part 76 on which is mounted a gear 77 meshing with a tumbler gear 78 adapted to engage any of the change gears 79, 80, 80 81 and 82, which are keyed to a shaft 83 mounted in bearings fixed to the saddle. The tumbler gear 78 is mounted on an arm 78^a pivoted on the hubs of gear 77, concentrically with shaft 76, and having on its end 85 a spring-pressed latch adapted to hold the gear in mesh. Gear 82 meshes with a gear 84, which is rotatably mounted on sleeve 41, and meshes with a wide face gear 86 fixed to a shaft 87 having slidably keyed thereon 90 a shifting gear 88 which is shifted by an arm 89 secured to a shaft 90 having fixed thereto a lever 91 outside of the saddle.

The operation of the feed change gears is as follows: the power is transmitted to shifting gear 88 from the speed change gearing, through friction gear 45; gears 46, 47 and 49; bevel gears 50, 51 and 52. When the feed change gears are rotating in one direction, clutch 54 engages clutch face 57 on bevel gear 50 and, when rotating in opposite direction, clutch 54 engages clutch face 58 on bevel gear 52, and transmits the power to shaft 53, gear 59, gear 60, 64 or 68, slidably keyed gear 70, shaft 71, gear 77, tumbler gear 78, gear 79, 80, 81 or 82, gear 84, wide face gear 86, shaft 87, to shifting gear 88.

The change feed gearing thus described is used to vary the endwise feed of the spindle; the vertical feed of the saddle, horizontal feed of the column or the movement of any other element deriving its power from the column feed shaft.

Spindle feed mechanism.

The spindle feed mechanism comprises a gear 92 keyed to a shaft 93 having a feed screw part 94 fitting within a screw threaded nut 95 fixed in a bearing 96 rotatably secured 100 to spindle 44.

Saddle adjusting mechanism.

The saddle adjusting mechanism comprises a gear 97 cast integrally with a spiral gear 98 rotatably mounted on a shaft 99. Spiral gear 98 meshes with another spiral gear 100 having a depending sleeve 101 internally threaded to receive a saddle adjusting screw 102 fixed in the top of the column.

The depending sleeve 101, which is journaled in a bearing 103, has ball bearings interposed between the bottom of its bearing 103 and a securing nut 104.

5 *Column adjusting mechanism.*

The column adjusting mechanism comprises a gear 105 cast with a spiral gear 106 rotatably mounted on the fixed shaft 99.

10 Spiral gear 106 meshes with a spiral gear 107 splined to a column feed shaft 108 mounted in bearings in the column. The column shaft 108 extends vertically from the saddle and is adapted for use in transmitting 15 movement to any suitable parts on a machine, such as the column, work-table, etc. The mechanism for effecting this transmission may be of any suitable type.

When it is desired to move the spindle 20 endwise, the saddle vertically or the column horizontally, shifting gear 88, may be actuated by lever 91, to mesh with gear 92, 97 or 105. A very rapid movement is effected by shifting gear 84 until a frusto-conical 25 clutch member 109 engages a clutch member 110 cast with a gear 111 rotatably mounted on sleeve 41, and held in place by a ring 112. Gear 111, meshes with a by-pass gear 113 fixed to the series shaft 14. It will be 30 seen that, by shifting clutch member 109 into engagement with clutch member 110, by a lever 114 through the medium of a hollow shaft 115, passing over shaft 90, and a yoke 116, gear 84 will be out of mesh with 35 gear 82 but still in mesh with the wide face gear 86 and a very rapid movement of the spindle, saddle or column is effected through a train of gears which by-passes the speed change and feed change gearing.

40 The hand-controlling mechanism comprises a hand-wheel 117 secured to shaft 118; mounted in bearings fixed to the saddle. Shaft 118 has at its end a fixed bevel gear 119 meshing with a bevel gear 120 fixed on shaft 87 which carries the shifting gear 88. If it is desired to control the feed of the 45 spindle, saddle or column by hand, shifting gear 88 is moved in mesh with the gear 92, 97 or 105, the same as when operated by power except that the change feed gearing 50 is disconnected with the motor 3, and thus a hand control is effected through very few parts.

55 Sleeve 41 which forms the immediate support for the spindle extends through the saddle and being journaled near each end in rigid bearings 42 and 43 is very rigidly supported and the spindle action is very steady.

60 When it is desired to feed the spindle endwise while rotating, lever 91 is moved to shift gear 88 into mesh with the gear 92 of the spindle feed mechanism. To feed the saddle vertically while the spindle is rotating, 65 lever 91 is moved to shift gear 88 into mesh

with gear 97 of the saddle adjusting mechanism. To feed the column horizontally while the spindle is rotating, lever 91 is moved to shift gear 88 into mesh with gear 105 of the column adjusting mechanism. 70

When it is desired to change the feed of the spindle, saddle or column, the feed change gears are shifted by lever 74 and arm 78. Lever 74 shifts gear 70 into mesh with either of series gears 60, 64 or 68. 75 Arm 78^a moves tumbler gears 78 into mesh with change gear 79, 80, 81 or 82. Thus the series gears 60, 64 and 68 impart three different feeds to the change gears 79, 80, 81 and 82, making a total of twelve different 80 feeds from the feed changing gearing.

When it is desired to reverse the feed change gears and consequently the spindle, saddle or column, assuming clutch 54 to be in engagement with clutch face 57 of gear 50, lever 56 is moved to shift the slidably keyed clutch 54 into clutching engagement with the opposite clutch face 58 of gear 52 and a reverse movement will be imparted, as gear 52 rotates in the opposite direction 90 to gear 50 due to the interpositioning of gear 51.

To disconnect the feed change gears, and consequently the spindle, saddle or column, from the speed change gears and motor, 95 clutch 54 is shifted by lever 56 out of engagement with clutch faces 57 and 58, and held in a neutral position between them. Thus the feed change gears are disconnected from the speed change gears, as bevel gears 50 and 52, having the clutch faces thereon, are rotatably mounted on shaft 53.

When it is desired to change the speed of the cutting tool; that is, the speed of rotation, and endwise feed, of the spindle; or the speed of rotation of the spindle, and vertical feed of the saddle; or the speed of rotation of the spindle, and the horizontal feed of the column, it may be done by simply shifting the speed change gears with levers 16^b and 38. By moving lever 38, downward and sidewise, the inner end will disengage notch 36 and engage notch 37, and move gears 27 and 28 through the medium of shifting rod 35. By moving lever 38 upward and sidewise, the inner end will disengage notch 37 and engage notch 36, and move gears 25 and 26 through the medium of shifting rod 32. 110

The lever 16^b moves the series gears 15 and 16 so that their clutch parts 15^a and 16^a will engage clutch member 17 or 18, and series gear 16 engages series gear 19. Three series of movements will be imparted to the intermediate gears 21, 22, 23 and 24 and consequently change gears 23, 26, 27 or 28 making a total of twelve speeds from the speed change gearing. 115

The feed of the spindle, saddle or column is changed proportionately, thus saving con- 120

siderable time by avoiding manipulation of a number of levers for the proportionate change in feed.

When a very rapid movement is desired of the spindle endwise, the saddle vertically, or the column horizontally, lever 114 is moved upward to effect an engagement of frusto-conical clutch member 109 with clutch member 110 and move gear 84, which is fixed to 10 the frusto-conical clutch member 109, out of mesh with gear 82 but keep in mesh with wide face gear 86. Thus a very rapid movement of either the spindle, saddle or column may be effected through by-pass gear 113, gear 111, clutch members 110 and 109, gear 84, and wide face gear 86.

To control by hand the endwise feed of the spindle; the vertical feed of the saddle; or horizontal feed of the column, the feed 20 change gears are disconnected from the speed change gears by moving lever 56 so that clutch 54 will be in a neutral position. The shifting gear 88 is moved by lever 91 into mesh with either gear 92, 97 or 105 respectively of the spindle, saddle and column mechanism, hand wheel 117 is turned and a movement of either the spindle, saddle or column is then effected.

The direction of motion of the several 30 chains of gearing may be reversed by reversing the motor, and the direction of motion of the feed change gearing may be independently reversed by moving lever 56 so that clutch 54 will engage the opposite face.

If it is desired to reverse the rotation of the spindle and continue the feed in the same direction, lever 56 is moved to engage clutch 54 with the opposite clutch face.

While I have described my invention as 40 taking a particular form, it will be understood that the various parts of my invention may be changed without departing from the spirit thereof, and hence I do not limit myself to the precise construction set forth, but 45 consider that I am at liberty to make such changes and alterations as fairly come within the scope of the appended claims.

Having thus described my invention, what 50 I claim as new and desire to secure by Letters Patent is:—

1. A metal working machine including a column shaft; a saddle; a spindle mounted in the saddle for rotation and endwise movement; speed change gears; feed change gears, and a common shifting gear whereby the speed and feed change gears may be connected for moving either the column shaft, the saddle or the spindle.

2. A metal working machine including a column shaft; a saddle; a spindle mounted in the saddle for rotation and endwise movement; driving means; speed change gears connected with the driving means; feed change gears; a common shifting gear whereby the speed change gears may be con-

nected with the feed change gears for moving either the column shaft, the saddle or the spindle; a by-pass gear, and means for connecting the by-pass gear with the common shifting gear for rapid movement.

3. A metal working machine including a column shaft; a saddle; a spindle mounted in the saddle for rotation and endwise movement; driving means; speed change gears connected with the driving means; feed 70 change gears; a common shifting gear whereby the speed change gears may be connected with the feed change gears for moving either the column shaft, the saddle or the spindle; a hand wheel, and connections between the hand wheel and the common shifting gear whereby the column shaft, saddle or spindle may be moved by hand.

4. A metal working machine including a column shaft; a saddle; a spindle mounted 85 in the saddle for rotation and endwise movement; driving means; speed change gears connected with the driving means; feed change gears; a common shifting gear whereby the speed change gears may be connected with the feed change gears for moving either the column shaft, the saddle or the spindle, and reversing means between the speed and feed change gears.

5. A metal working machine including a column shaft; a saddle; a sleeve rotatably mounted in and extending through the saddle; a spindle; slidably keyed in the sleeve; speed change gears; feed change gears, and a common shifting gear whereby the speed and feed change gears may be connected for moving either the column shaft, the saddle or the spindle.

6. A metal working machine including a column shaft; a saddle; a spindle mounted 105 in the saddle for rotation and endwise movement; speed change gears; feed change gears; means yieldingly connecting the speed change gears and the feed change gears, and a common shifting gear whereby the speed and feed change gears may be connected for moving either the column shaft, the saddle or the spindle.

7. A metal working machine including a column shaft; a saddle; a sleeve rotatably mounted in and extending through the saddle; a spindle slidably keyed in the sleeve; speed change gears connected to the sleeve; feed change gears connected to the speed change gears; means including a shifting gear for connecting the feed change gears for moving either the shaft column, saddle or spindle; a by-pass gear, and means on the sleeve for disconnecting the feed change gears from, and connecting the by-pass gear with the shifting gear for rapid movement.

8. A metal working machine including a column shaft; a saddle; a sleeve rotatably mounted in and extending through the saddle; a spindle slidably keyed in the sleeve;

- speed change gears connected to the sleeve; feed change gears connected to the speed change gears; means including a shifting gear for connecting the feed change gears for moving either the column shaft, saddle or spindle; a by-pass gear, and a sliding gear and clutch on the sleeve for disconnecting the feed change gears from and connecting the by-pass gear with the shifting gear for rapid movement.
9. A metal working machine including a column shaft; a saddle; a sleeve rotatably mounted in and extending through the saddle; a spindle slidably keyed in the sleeve; speed change gears connected to the sleeve; speed series gears connected to the speed change gears; feed change gears connected to the speed change gears; means including a shifting gear for connecting the feed change gears for moving either the column shaft, saddle or spindle; a by-pass gear, and a sliding gear and clutch on the sleeve for disconnecting the feed change gears from and connecting the by-pass gear to the shifting gear for rapid movement.
10. A metal working machine including a column shaft; a saddle; a sleeve rotatably mounted in and extending through the saddle; a spindle slidably keyed in the sleeve; speed change gears connected to the sleeve; speed series gears connected to the speed change gears; reversing means connecting the speed change gears to the feed change gears; means including a shifting gear for connecting the feed change gears for moving either the column shaft, saddle or spindle; a by-pass gear, and a sliding gear and clutch on the sleeve for disconnecting the feed change gears from and connecting the by-pass gear to the shifting gear for rapid movement.
11. A metal working machine including a column shaft; a saddle; a sleeve rotatably mounted in and extending through the saddle; a spindle slidably keyed in the sleeve; speed change gears connected to the sleeve; speed series gears connected to the speed change gears; reversing means between the speed change gears and the feed series gears; feed change gears connected to the feed series gears; means including a shifting gear for connecting feed change gears for moving either the column shaft, saddle or
- spindle; a by-pass gear, and a sliding gear and clutch on the sleeve for disconnecting the feed change gears from and connecting the by-pass gears to the shifting gear for rapid movement.
12. A metal working machine including; a saddle; a sleeve rotatably mounted in and extending through the saddle; a spindle slidably keyed in the sleeve; a bull gear on an end of the sleeve; a shaft for driving the bull gear having speed change gears thereon; a shaft having intermediate gears to mesh with respective change gears; a driving shaft having clutch members and sliding gears adapted to mesh with the intermediate gears and engage the clutch members, and a shaft having a by-pass gear and a gear to mesh with a sliding gear.
13. A metal working machine including; a saddle; a sleeve rotatably mounted in and extending through the saddle; a spindle slidably keyed in the sleeve; a bull gear on an end of the sleeve; a shaft for driving the bull gear having speed change gears and a friction gear thereon; a shaft having intermediate gears to mesh with respective change gears; a driving shaft having clutch members and series gears adapted to mesh with the intermediate gears and engage the clutch members; a shaft having a by-pass gear and a gear to mesh with a sliding gear, and reversing means between the friction gear and feed change gears.
14. A metal working machine including; a saddle; a sleeve rotatably mounted in and extending through the saddle; a spindle slidably keyed in the sleeve; a bull gear on an end of the sleeve; a shaft for driving the bull gear having speed change gears and a friction gear thereon; a shaft having intermediate gears to mesh with respective change gears; a driving shaft having clutch members and sliding gears adapted to mesh with the intermediate gears and engage the clutch members; a shaft having a by-pass gear and a gear to mesh with the sliding gear; feed series gears; reversing means between the friction gear and the feed series gears, and feed change gears connected to the feed series gears.

In testimony whereof I have signed my name to this specification.

FRANK S. JONES.
